KEYLESS THREE WAY LIGHT SOCKET

Hung-tu Tseng, New York, N. Y.

Application May 5, 1953, Serial No. 353,265

1 Claim. (Cl. 240—81)

This invention relates to new and useful improvements in three pole electric lamp sockets and lamp fixtures and structures having such sockets.

More particularly, the present invention proposes the construction of an improved three pole lamp socket which can be operated by a three way switch mounted at a point remote from the socket such as at the base of a lamp, or on a wall or even in another room.

Another object of the present invention proposes forming the three pole lamp socket substantially the same as present commercially available uniform sockets, but providing an extra wire connecting terminal on the socket so that the socket may be easily and conveniently connected by two socket terminals with two switch terminals of a three way switch located remotely from the socket and the socket and switch be connected by their third terminals with the two power lines of a source of electric energy such as a household electric power line.

Still further, the present invention proposes constructing a lamp fixture or lamp structure which contains a three pole switch and an improved three pole lamp socket which can be physically separated but which are simply and efficiently connected together electrically.

As a further object, the present invention proposes the construction of a lamp or a lamp fixture or structure containing two or more of such improved three pole lamp sockets which can be operated by a single three way switch located remotely from the sockets.

For further comprehension of the invention, and of the objects and advantages thereof, reference will be had to the following description and accompanying drawings, and to the appended claim in which the various novel features of the invention are more particularly set forth.

On the accompanying drawings forming a material part of this disclosure:

Fig. 1 is a side view of a lamp structure having the improved three pole lamp socket and a commercially available three way switch mounted on the stand and constructed and arranged in accordance with the present invention.

Fig. 2 is a side view of the socket shown in Fig. 1.

Fig. 3 is an enlarged sectional view taken on line 3—3 of Fig. 2.

Fig. 4 is a complete bottom end view of the structure shown in section in Fig. 3.

Fig. 5 is a sectional view taken on the line 5—5 of Fig. 3.

Fig. 6 is an enlarged exploded view of the parts shown in Fig. 3, but with the metal casing and insulator shell omitted.

Fig. 7 is a perspective view of the three way switch shown in Fig. 1 with socket terminal members shown in Fig. 6, the parts being connected together and to two power lines in accordance with the present invention.

Referring more particularly to the drawing, a lamp structure 15 is shown in Fig. 1 having a stand 16, an upright member 17, the improved three pole socket 18 con-

2

nected to the upright member 17, a three way switch 19 mounted on the stand and a lamp shade 20 secured to the socket 18. The upright member 17 is of hollow tubing to permit wiring of the switch to the socket and the socket to a source of electric energy (not shown) as will later be fully described.

The improved three pole socket 18 is similar in size and shape to the conventional standard three pole sockets which receive standard three pole electric lamps (not shown) mechanically supporting the lamps and electrically connecting them to the circuit wires.

Three pole socket 18 has a hollow cylindrical tubular shell 21 covered at its upper end by a cap 22 frictionally held to it. The cap 22 has the usual threaded central top opening 23 and a paper or other non-conductor material disc 24 (see Fig. 3) in the cap 22 has a similar aligned opening 25. Shell 21 has the usual paper or other non-conductor material tube 26 closely fitting within it.

20 A base member 27 of insulator material such as thermosetting plastic or porcelain fits within the tube 26 and shell 21.

On the base member 27 of the socket are three spaced wire connecting terminals 28, 29 and 30 (see Fig. 6), the base member 27 being provided with grooved recesses 31, 32 and 33 to receive and hold the terminals 28, 29 and 30 respectively.

30 A threaded electric lamp receiving sleeve 34 of conductor material is secured to the base member 27 by screws 35 and 36 with an insulator disc or sheet 37 disposed between the sleeve 34 and the base member 27 of the socket. The sleeve 34 has a central axial opening 38 at its upper end between the screws 35 and 36.

35 The socket terminal 28 in recess 31 consists of a wire connecting terminal member 39 with a terminal screw 40 extending through it. Screw 35 which holds the sleeve 34 to the base member 27 is made of conductor material and connects with the member 39 of the socket terminal 28. This provides means electrically to connect member 39 to sleeve 34 as well as to secure the member 39 to the base member 27 of the socket. In this manner also, the sleeve 34 is made one pole of the three pole socket 18.

40 45 45 The socket terminal 29 consists of a conductor member 41 secured to the base member in recess 32 and a second wire connecting terminal screw 42 in the upper end of the conductor member 41. The lower end of the conductor member 41 extends through the insulator disc or sheet 37 and central axial opening 38 of the sleeve 34 into the sleeve to form another pole of the socket 18.

50 55 55 The socket terminal 30 in recess 33 consists of another conductor member 43 having a lower bent spring conductor end 44 and a third wire connecting terminal screw 45 in the upper end of the conductor member 43. The lower end 44 of conductor member 43 also extends through the insulator disc or sheet 37 and central axial opening 38 of sleeve 34 into the sleeve to form the third pole of the socket 18.

60 The three way switch 19 is a common type three way switch adapted for mounting and mounted at a point remote from the socket. While this point is shown in Fig. 1 as the stand or base 16 of the lamp, it may of course be any point on the lamp fixture or structure or remote therefrom.

65 The three way switch 19 has three terminals 46, 47 and 48 (see Fig. 7). Switch terminal 46 is connected by conduit or wire 49 to a source of electric energy (not shown) the wire 49 being one circuit wire or one line of a power line. Similarly, socket terminal 28 is connected by conduit or wire 50 to the source of electric energy, the wire 50 being the second circuit wire or line of a two line power circuit line.

Switch terminal 47 is connected by conduit or wire 51 to the socket terminal 30 and switch terminal 48 is connected by conduit or wire 52 to the other socket terminal 29. In this manner, the switch 19 and socket 18 form a lamp fixture wherein a three pole socket of simple and substantially similar to standard designs may be actuated by a switch mountable remote from the socket.

It will be apparent that two or more of the improved three way light sockets 18 may be incorporated in a lamp or a lamp fixture or lamp structure and operated by one three way switch. The socket 18 can be made to receive any type three light bulb such as one with 30 watts, 70 watts, and 100 watts, or any bulb under 250 watts, or for larger light bulbs over 250 watts.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

A lamp socket comprising a solid cylindrical insulating base member, an outer sleeve supported thereby, said base member having a pair of opposed recesses therealong from end to end thereof, and a third recess inter-

mediate said pair of recesses terminating short of one end, a conducting sleeve secured to said base member and depending therefrom inside said outer sleeve, said conducting sleeve being open at both ends, a terminal member mounted in each opposed recess of the base, binding screws connected to said terminal members, a central lamp contact connected to one of the opposed terminal members, said central contact being disposed in the opening in the inner end of the conducting sleeve in spaced relation, conductors leading from the binding screws of said opposed terminals to a remote three-pole switch connected to a source of electro motive force and a conductor leading from the binding screw of the terminal in the intermediate recess to a source of electro motive force.
